UNITED STATES PATENT OFFICE

VIRGIL L. FRANTZ, OF ROANOKE, VIRGINIA, ASSIGNOR TO GRAHAM-WHITE SANDER CORPORATION, OF ROANOKE, VIRGINIA, A CORPORATION OF VIRGINIA

LOCOMOTIVE SANDING MECHANISM

Application filed November 18, 1930. Serial No. 496,497.

This invention relates to sanding devices for the wheels of locomotives and has for its general object the provision of a novel sanding mechanism wherein the number of necessary parts and the length of piping may be greatly reduced without in any way impairing the efficiency.

It is well known that a popular type of locomotive sanding mechanism involves the provision of sanding devices located on opposite sides of a locomotive boiler and controlled by a Duplex valve within the cab, this valve having the necessary pipe connections with a source of fluid pressure and with the sanders themselves, the sanders being on both sides of the locomotive and having branch pipe connections thereto so that only one duplex valve is needed for the control of the entire mechanism. For instance in Patent No. 1,409,538 granted March 14th, 1922, to James Frantz, there is disclosed a Duplex valve embodying a valve casing having a fluid pressure inlet and a plurality of outlets leading to or at least adapted to lead to the sanders on opposite sides of the locomotive boiler. It will be observed by referring to said patent that when it is desired to sand the forward wheels of the locomotive truck it is necessary to move the valve handle forwardly so that a cleaning blast and a sanding blast of air will be supplied to the sand traps and nozzles. When the locomotive is backed and it is desired to effect sanding to prevent slippage during such reverse motion, it is necessary to move the valve handle backwardly whereupon a certain piston valve mechanism will operate to establish communication between the fluid pressure supply and those sanders which have delivery pipes discharging to the rear of the rear wheels of the locomotive truck. This is old art not only as disclosed in this particular patent but as disclosed by other patents owned by the Graham-White Sander Corporation, the assignee of the present case. If necessary reference may readily be had to additional patents disclosing this same general scheme.

By way of explanation it may also be said that in all locomotive sanding devices it becomes imperative to insure that there will be

no clogging of the sanding nozzles and delivery pipes. If the sand be the least bit damp it is of course obvious that in freezing weather it will solidify and will therefore not respond to an air blast. It is not feasible to have the sand absolutely dry and on account of the possibility of slight moisture steps must be taken to insure freeing of the sand discharging nozzles or orifices of any accumulation that might occur under any circumstances. It is for this reason that in devices of this type means is provided not only for applying an air blast for discharging the sand onto the rails adjacent the wheels but also for providing a preliminary blast of very short duration which will operate to remove any accumulation of sand remaining in the nozzles or discharge orifices from a previous operation of the mechanism.

It is with the above facts in view that I have devised the present invention which has for an important object the provision of a locomotive sanding mechanism embodying an automatic valve which is operated by fluid pressure upon the opening of the main or Duplex valve, for the purpose of controlling the discharge of a cleaning blast applied to the sanding traps.

A further object of the invention is to provide a sanding system of this character which will be selective in so far as concerns the sanding of the front and rear wheels of the locomotive truck and which embodies an automatic valve mechanism controlling the cleaning blast applied to the sanders, the arrangement being such that only one automatic valve will be needed for both sets of sanders, this latter mentioned detail being of extreme importance in reducing the cost of the equipment, particularly as regards the length of the piping necessary to bring about the desired results.

Another object of the invention is the provision of a novel automatic valve interposed between the Duplex control valve and the sanders for the purpose of insuring a short or almost momentary blast of air through the cleaning ports or orifices.

Another object of the invention is to provide a sanding mechanism or system where-

in the sanding of the respective sets of wheels of the locomotive is easily controlled or effected by operation of the main or Duplex valve located within the locomotive cab and 5 wherein the cleaning operation is automatically effected by the special valve, only one of which is necessary for the two sanders.

Another specific object of the invention is to provide a novel construction of automatic valve which is operated purely by fluid pressure and which is provided within itself with means for permitting flow of fluid pressure to the cleaning pipes for a limited time, and then for cutting off said flow so 10 that the entire degree of fluid pressure may be exerted upon the sand applying mechanism.

An additional object is to provide an arrangement and combination of parts having 20 these characteristics and which will yet be simple and inexpensive to make, easy to assemble, positive in action, efficient and durable in service, and a general improvement in the art.

25 To the attainment of the foregoing and other objects and advantages, the invention preferably consists in the details of construction and the arrangement and combination of parts to be hereinafter more fully 30 described and claimed, and illustrated in the accompanying drawing in which:

Figure 1 is a diagrammatic side elevation of the mechanism as applied to a locomotive,

35 Figure 2 is a similar view showing an alternative arrangement, and

Figure 3 is a detail vertical section through the automatic valve.

Referring more particularly to the drawing and especially Figure 1 the numeral 10 40 designates, broadly, a Duplex valve which may for example be somewhat similar to that disclosed in the patent of James Frantz granted March 14th, 1922 and numbered 1,409,538. In order to make the present invention entirely clear, it is probably better 45 to mention that this valve comprises a casting or body 11 into which extends a pipe 12 leading from a source of fluid pressure which might be a compressed air pump or the like.

50 This valve has two outlets 13 and 14 from which air under pressure is permitted to be discharged upon oscillation, as it might be called, of a handle 15 which is pivoted at 16 and which includes a transverse member 55 17 abutting against the ends of plungers 18 and 19 forming part of valve devices for controlling the passage of compressed air from the pipe 12 to the discharge ports 13 and 14, respectively.

60 The mechanism also includes sanders or sand traps 20 and 21 which are similar and which may be arranged as indicated or disclosed in the co-pending application of Virgil L. Frantz and Oren O. Lemon, filed 65 February 13th, 1929, Serial No. 339,715, or as

indicated in other patents assigned to the Graham-White Sander Corporation. The valve devices 20 and 21 comprise body members having delivery pipes 22 and 23 respectively, sanding or inlet pipes 24 and 25, 70 respectively, and cleaning pipes 26 and 27 connected therewith. The pipe 26 connects with the outlet 13 of the main control or Duplex valve, while the pipe 27 connects with the outlet port 14. Shunted about the pipes 27 and 25 is a pipe 28 within which is interposed a check valve 29 and an automatic control valve 30 which constitutes one of the important features of the present invention, note being taken that the pipe 28 connects 80 directly with the pipe 27 and through the valve 30 and pipe 34 with the pipe 24.

At this point it is necessary to explain that the automatic valve 30 comprises a casting 31 having a suitable inlet nipple 32 with in which the pipe 28 is connected, and having an outlet nipple 33 within which is connected the pipe 34 which connects with the pipes 24 and 25 leading to the sanders 20 and 21, respectively. Within the valve casting 31 is a longitudinally movable valve assembly including a piston 35 connected by a piston rod or stem 36 with a piston 37 of considerably less diameter, the latter mentioned piston 37 being engaged by a coil spring 38 which operates normally to hold the valve assembly in such position that there is a constant communication between the pipes 28 and 34. However, the larger piston member or head 35 is formed with an opening 39 which will permit fluid pressure to pass through this piston head and build up beneath it so that the combination of this fluid pressure acting upon the piston head 35 (which is of larger diameter than the piston head 37) will move the valve longitudinally upwardly, as the drawing is viewed, and cut off communication to the pipe 34, it being readily apparent that the piston head 35 will close, cover or obstruct the exit to the pipe 34 at such time. While it is not essential, the valve casing 31 is shown as provided interiorly with a seat 40 which will be engaged by the correspondingly beveled top edge 41 of the head 35 when the valve mechanism or 100 movable valve device moves upwardly.

In Figure 2 there is disclosed an arrangement wherein connected with the outlet port 13 is a pipe 42 which connects with branch pipes 43 and 44, the former of which leads 105 to the automatic valve 30, and the latter of which leads to the sanding port of the sand trap 20. Connected with the outlet port 14 is a pipe 45 which leads to the sanding port of the sand trap 21. Interposed in the pipe 43 is a check valve 46 which opens 110 toward the automatic valve 30. Furthermore, connecting the pipes 43 and 45 there is a branch pipe 47 having interposed therein a check valve 48. In other respects the ar- 115 120 125 130

arrangement in Figure 2 is substantially the same as that disclosed in Figure 1.

In the operation of the device, referring especially to Figure 1, it will be observed that when the handle 15 is pushed forwardly, that is to say to the right of the drawing, the port 13 in the valve 10 is opened and fluid pressure is admitted to the pipe 26 leading to the sanding port of the sand trap 20. At the same time fluid pressure passes through the branch pipe to the automatic valve 30, the check valve 29 being of such construction as to prevent air pressure from passing through the pipe 28. Normally, the automatic valve 30 permits air under pressure to pass therethrough until air passing through the port 39 in the head 35 builds up a pressure beneath this head sufficient to move the reciprocable valve into such position that the beveled upper edge of the head 35 contacts with the beveled seat 40 at the intermediate portion of the valve casing. When this occurs communication to the pipe 34 leading to the cleaning orifices of both of the sand traps 20 and 21 is cut off. The automatic valve therefore operates to control the cleaning of both of the traps 20 and 21 so that there can be no clogging thereof under any circumstances whatsoever. When it is desired to operate the sanding devices or sand traps 21 for the rear wheels of the truck, it is merely necessary to pull the valve handle 15 backwardly or to the left, as viewed in Figure 1 of the drawing, whereupon air pressure from the pipe 12 is permitted to pass out through the port 14 and to the pipe 27 leading to the sanding port of the sand trap 21. In view of the fact that the pipe 27 is connected by the pipe 28 to the automatic valve 30 through the check valve 29 it is quite apparent that pressure will be supplied to the sanding port of the sander 20. Both sanders will therefore be operated. Pressure will also be supplied to the cleaning ports of both sanders as above described, through the action of the valve 30.

In the modification disclosed in Figure 2 it will be seen that when the valve handle 15 is moved forwardly, or to the right of the drawing, air pressure from the pipe 12 will be discharged from the exit orifice 13 to the pipe 42 and thence to the sand trap 20 from which of course the sand is forced through the pipe 22 in the well known manner. Attention is directed to the fact that at this time air pressure also passes through the check valve 46 and automatic valve 30 to the cleaning orifice of the sand trap 20. The actual operation of the automatic valve 30 itself has already been explained and it is therefore thought that a repetition thereof should be unnecessary. When the valve handle 15 is pulled backwardly, or to the left, viewing Figure 2 of the drawing, it is apparent that air pressure from the pipe 12 will pass out of

the port 14 and through the pipe 45 to the sanding nozzle of the trap 21. In view of the fact that the branch pipe 47 connects the pipes 42 and 45 and that this pipe 47 has the check valve 48 interposed therein, it is quite clear that the automatic valve 30 will operate in identically the same manner for clearing out the sanding nozzles of both traps as above explained in connection with Figure 1.

From the foregoing description and a study of the drawing it will be quite apparent that I have thus provided a very simple and inexpensive sanding mechanism which possesses the advantage of requiring only one automatic valve for taking care of the cleaning of a plurality of traps. It is well known that it is a common practice to have a cleaning device for each sander or sand trap but by my particular arrangement I have found it possible to employ a single automatic valve operated by fluid pressure and acting to take care of the blowing out or cleaning of the nozzles in the respective sand traps. Consequently it is quite apparent that the amount of piping is reduced and that the number of valves for taking care of the cleaning proposition may be reduced by half, the sum total of the invention therefore residing in the elimination of a duplication of parts and devices which would otherwise materially add to the installation as well as the maintenance of the system.

While I have shown and described the preferred embodiments of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In a locomotive sanding mechanism, the combination of a source of fluid pressure, a two-way valve connected therewith, a plurality of sand traps each having a delivery pipe, a cleaning port and a main fluid pressure admission port, and means connected with said valve and connected with the cleaning ports of the sand traps and automatically operable for supplying fluid pressure to the cleaning ports of all of the traps when the two-way valve is opened in either direction.

2. In a locomotive sanding mechanism, the combination of a source of fluid pressure, a two-way valve connected therewith, a plurality of sand traps each having a delivery pipe, a cleaning port and a main fluid pressure admission port, and means connected with said valve and connected with the cleaning ports of the sand traps and automatically

operable for supplying fluid pressure to the cleaning ports of all of the traps when the two-way valve is opened in either direction, said means comprising a fluid pressure actuated valve.

- 5 3. In a locomotive sanding mechanism, the combination of a two-way valve connected with a source of fluid pressure, a plurality of sand traps each having a delivery pipe, a main air inlet port and a cleaning port, the main inlet ports of said sand traps being connected with the respective outlets of the two-way valve, and a fluid pressure operated valve connected with said two-way valve for actuation by opening thereof in either direction and connected with the cleaning ports of the sand traps.

- 10 4. In a locomotive sanding mechanism, the combination of a plurality of sand traps arranged for delivering sand to different pairs of wheels of a locomotive truck, a valve for controlling the supply of fluid pressure to said sand traps, said sand traps having cleaning ports, and fluid pressure operated valve 15 means connected with said control valve and said sand traps for applying a cleaning blast to all of the sand traps when said control valve is operated to apply fluid pressure to either selected sand trap.

- 20 5. In a locomotive sanding mechanism, the combination of a plurality of sand traps separately operable for delivering sand to selected pairs of wheels of a locomotive truck, a two-way valve connected with a source of 25 fluid pressure and with the delivery ports of the respective sand traps, and a fluid pressure operated valve connected with said two-way valve and shunted about all of the sand traps for applying a cleaning blast thereto 30 whenever the two-way valve is operated in either direction.

- 35 6. In a locomotive sanding mechanism of the character described including a plurality of sand traps having cleaning ports and a control valve for applying fluid pressure thereto, an automatic fluid pressure operated valve connected with said valve and with the cleaning ports of the sand traps, said automatic valve comprising a casing having an 40 inlet and an outlet, a longitudinally movable member therein having piston heads of different diameters, one head being apertured for the passage of fluid pressure to enable the same to build up beneath it and overbalance the differential relation between the heads for moving said longitudinally movable member to close the outlet.

- 45 7. In a locomotive sanding mechanism, the combination of a source of fluid pressure, 50 manually operable valve means connected therewith, a plurality of sand traps each having a delivery pipe, a cleaning port and a main fluid pressure admission port, and means connected with said valve means and 55 with the cleaning ports of the sand traps and

automatically operable for supplying fluid pressure to the cleaning ports of all of the traps when said valve means is opened.

8. In a locomotive sanding mechanism, the combination of a source of fluid pressure, 70 manually operable valve means connected therewith, a plurality of sand traps each having a delivery pipe, a cleaning port and a main fluid pressure admission port, said valve means being connected with the fluid 75 pressure admission ports of the respective traps, and means connected with said valve means and with the cleaning ports of the traps and automatically operable for supplying fluid pressure to the cleaning ports of 80 all the traps when the valve means is operated to supply fluid pressure to the main admission port of either trap.

In testimony whereof I affix my signature.

VIRGIL L. FRANTZ.
